(57) CLAIM

The ornamental design for an active self-warming blanket, as shown and described.

DESCRIPTION

FIG. 1 is a perspective view of an active self-warming blanket showing our new design;

FIG. 2 is a top elevational view thereof;

FIG. 3 is a left side elevational view thereof;

FIG. 4 is a front plan view thereof;

FIG. 5 is a rear plan view thereof;

FIG. 6 is a right side elevational view thereof; and,

FIG. 7 is a bottom elevational view thereof.

The dot-dot-dashed line disclosure in FIGS. 1-7 forms the outer environmental structure and forms no part of the claimed design. The evenly spaced short dashed line disclosure in FIGS. 1-7 represents seams and forms a part of the claimed design.
